UNITED STATES PATENT OFFICE

113,655

DESIGN FOR A TEETHING RING OR SIMILAR ARTICLE

Joseph Davis, Arlington, N. J.

Application December 17, 1938, Serial No. 81,851

Term of patent 14 years

To all whom it may concern:

Be it known that I, Joseph Davis, a citizen of the United States, residing at Arlington, in the county of Hudson and State of New Jersey, have invented a new, original, and ornamental Design for a Teething Ring or Similar Article, of which the following is a specification, reference being had to the accompanying drawing, forming a part thereof.

In the drawing

Fig. 1 is a front view of a teething ring or similar article showing my new design.

Fig. 2 is an edge view and

Fig. 3 is a back view of the same.

The principal features of the design are shown in full lines in the drawing.

I claim:

The ornamental design for a teething ring or similar article, substantially as shown and described.

JOSEPH DAVIS.
